(57) **CLAIM**

The ornamental design for a double-sided mirror, as shown and described.

DESCRIPTION

FIG. 1 is a front, left, and top perspective view of a double-sided mirror of the present invention;

FIG. 2 is a front elevation view of the invention illustrated in FIG. 1;

FIG. 3 is a rear elevation view of the invention illustrated in FIG. 1;

FIG. 4 is a left elevation view of the invention illustrated in FIG. 1;

FIG. 5 is a right elevation view of the invention illustrated in FIG. 1;

FIG. 6 is a top view of the invention illustrated in FIG. 1;

FIG. 7 is a bottom view of the invention illustrated in FIG. 1;

FIG. 8 is a rear, left, and bottom perspective view of the invention illustrated in FIG. 1; and,

FIG. 9 is a cross-sectional view taken along lines 9-9 of FIG. 6.

The diagonal lines in the circular region of FIGS. 1, 6, 7, and 8 indicate a reflective mirror surface.

1 Claim, 7 Drawing Sheets
